HAROLD E. ELLIS AND FRANK THEODORE WILLIAMS, OF MERIDEN, CONNECTICUT, ASSIGNORS TO THE MILLER COMPANY, OF MERIDEN, CONNECTICUT, A CORPORATION OF CONNECTICUT

BROODER HEATER

Application filed August 21, 1929. Serial No. 387,322.

The present invention relates to brooder heaters and is more particularly directed toward the provision of a brooder heater with suitable means for manually and automatically adjusting the burner to vary the amount of fuel consumed.

The conditions under which brooders are operated require varying the amount of heat supply, and the present invention contemplates the provision of a device whereby the temperature may be controlled either manually or automatically.

According to the present invention, the burner and fuel tank are mounted in such a manner that the height of the burner can be varied so as to vary the height of flame under the brooder or other device being heated. The varying of the height of the flame is accomplished either by a thermostat responsive to temperatures of the brooder or it may be varied manually, or both manual and automatic control may be employed.

The accompanying drawings show, for purposes of illustration, one of the many possible embodiments in which the invention may take form, it being understood that the drawings are illustrative of the invention rather than limiting the same.

In these drawings:

30 Figure 1 is a top plan view of the brooder heater;

Figure 2 is a side elevational view of the same; and

Figure 3 is a section taken on the line 3-3 of Figure 2 looking in the direction of the arrow.

The brooder heater is carried on a sheet metal supporting base, indicated at 10. This base is of convenient size and configuration to be placed in the brooder and to carry the parts. The base 10 is provided with a tank support 11 on which is pivotally carried a tank 12, the tank being adapted to pivot about a horizontal axis indicated at 13. This tank is connected to a fuel pipe 14 which is carried substantially horizontal over the center of the base 10. The outer free end 15 of the pipe 14 is closed with a nut 16 and it is guided for vertical movement in a pipe guide 17 welded or otherwise secured to the base

plate 10. The pipe 14 carries a vaporizer 18 of the conventional type and adapted to carry a wick and burner.

It will be apparent that the movement of the pipe 14 and tank about the shaft 13 will cause a raising and lowering of the vaporizer 18 and that this will vary the height of the flame produced in the burner.

According to the present invention, means are provided for raising and lowering the pipe and burner and to this end, there is provided an adjustable pipe support or carrier indicated at A. This support includes a slidable plate 20 having an inclined upper edge on which the pipe directly rests. This plate 20 is supported on top of a vertically movable carriage 21, the carriage being made of sheet metal and provided with downwardly extending legs 22 reduced at their lower ends 23 to pass through slots in the base 10. Interposed between the carriage 21 and the top of the base 10 is a thermostatic member 24. This may be of the usual type provided for use in incubators and brooders, and when expanded, is adapted to raise the carriage 21 up to the dot and dash line position as indicated in Figures 2 and 3. The carriage is guided in this movement by the reduced ends 23 of the legs 22. When the carriage thus moves up, the plate 20 is raised and with it the pipe 14, thereby reducing the flow of fuel to the burner and lowering the flame. The base plate 10 is provided with reinforcing plate 25 in the form of an angle of sheet metal welded or otherwise secured to the plate and placed underneath the bellows 24.

The manual means for adjusting the flame includes a hand operated crank rod 30 pivoted on a bracket 31 carried by the tank support 11 and passing through a lug 32 struck up from the carriage 21. The crank rod 30 has an upwardly bent crank arm 33 which passes through a slot 34 in the transversely slidable pipe support 20 which is guided by lugs 35 struck up from the sheet metal of the carriage 21. When one operates the handle 30, motion is imparted to the slidable plate 20 to move it to the right or left thereby causing the pipe 14 to be raised or lowered as the 100

inclined portion 35 of the plate 20 passes underneath the pipe.

It will thus be seen that one can obtain a manual variation of the height of flame or can rely on the thermostatic operation for this purpose. It will be obvious that one can omit one or the other of these features if reliance is to be based on only one mode of control.

It is obvious that the invention may be embodied in many forms and constructions, and we wish it to be understood that the particular form shown is but one of the many forms. Various modifications and changes being possible, we do not limit ourselves in any way with respect thereto.

What is claimed is:

1. A burner regulator for brooders and the like, comprising, a supporting base, a fuel tank pivotally supported above the base and connected to a fuel pipe, a fuel burner carried by the free end of the fuel pipe, a vertically movable pipe carrier and a thermostat between the base and pipe carrier for controlling the height of the pipe and burner, the carrier having a manually movable wedge-shaped member for varying the height of the pipe and burner independently of the thermostat.

2. In a brooder heater, the combination with a fuel tank, fuel pipe and burner mounted to permit adjustment of the height of the burner, of a regulator, comprising, a fuel pipe support comprising a transversely slidable member having an inclined upper surface to vary the height of the fuel pipe.

3. In a brooder heater, the combination with a fuel tank, fuel pipe and burner mounted to permit adjustment of the height of the burner, of a regulator, comprising, a fuel pipe support comprising a transversely slidable member having an inclined upper surface to vary the height of the fuel pipe, and a thermostatically operated vertically movable carrier for the transversely movable member whereby the height of the fuel pipe varies with the temperature.

4. A device for adjusting the height of fuel burners, comprising, a supporting base, a pipe carrier having downwardly extending legs guided in the supporting base, stops to limit the downward movement of the carrier, a transversely movable wedge-shaped member between the pipe and carrier, and a thermostat interposed between the supporting base and the carrier, the thermostat acting to move the carrier relative to the base on increase in temperature to thereby raise the pipe.

5. A device for adjusting the height of fuel burners, comprising, a supporting base, a sheet metal pipe carrier having downwardly bent legs with reduced ends passing through slots in the base, a thermostat disposed between the legs of the carrier and intermediate the base and carrier and acting when heated

to raise the carrier, and a transversely movable member supported on the carrier and having an inclined upper edge on which the pipe rests.

6. A pipe adjuster for fuel burners, comprising, a carrier having downwardly extending legs with reduced ends, and an upper platform with upwardly struck guiding members, a wedge-shaped member slidably carried between the guiding members, and a crank arm pivotally connected to the carrier and with the wedge-shaped member for sliding the member.

7. In combination, a supporting base having a tank support at one end, a pipe guide at the other end, a tank pivoted to the tank support and having a pipe connected thereto and extending to the pipe guide, a fuel vaporizer and burner carried by the latter mentioned end of the pipe, a transversely movable wedge-shaped member on which the pipe rests, and an actuating handle for the wedge-shaped member mounted adjacent the tank, whereby the wedge-shaped member may be moved to adjust the height of the pipe and burner.

8. In combination, a supporting base having a tank supported at one end, a pipe guide at the other end, a tank pivoted to the tank support and having a pipe connected thereto and extending to the pipe guide, a fuel vaporizer and burner carried by the latter mentioned end of the pipe, a vertically movable pipe carrier on which the pipe rests, the pipe carrier normally resting on the supporting base, and a thermostat mounted between the base and carrier for raising the carrier.

Signed at Meriden, in the county of New Haven, and State of Connecticut, this 19th day of August, 1929.

HAROLD E. ELLIS.
FRANK THEODORE WILLIAMS.
